UNITED STATES PATENT OFFICE.

WILLIAM H. PRITCHETT AND OLAF J. CHRISTIANSEN, OF SAN DIEGO, CALIFORNIA.

HAIR CURLER.

Application filed May 21, 1925. Serial No. 31,874.

To all whom it may concern:

Be it known that we, WILLIAM H. PRITCHETT and OLAF J. CHRISTIANSEN, citizens of the United States, residing at San Diego, in the county of San Diego and State of California, have invented certain new and useful Improvements in Hair Curlers; and we do hereby declare the following to be a full, clear, and exact description of the invention, such as will enable others skilled in the art to which it appertains to make and use the same.

The present invention relates to hair curlers, and has for an object to provide a device of this character which is more efficient in operation and may be more economically manufactured and more effective in use than structures heretofore invented and used.

In hair curlers of this type considerable difficulty has been met with owing to the fact that the hinged parts are not capable of being swung outwardly from the body of the device into a straight line therewith, and out of the way; with the result that it requires a certain amount of skill to handle the prior hair curlers. A part of such structures have heretofore been made in one piece of spring metal, which does not overcome this difficulty, but which rather enhances it, because the spring members cannot be swung out of the way to permit of the free rolling of the curler in close contact with the hair.

An object of the present invention is to provide a hair curler, which has two hinged or clamping parts arranged in different relations with respect to the body of the curler, so that the device may be clamped fixedly and from slipping upon the outer or free ends of a cluster of hairs and the other may be employed for clamping the device closely adjacent the scalp after the device has been rolled tightly within the roll of hairs.

Another feature of the invention is to provide a device which may have a one piece body part capable of being stamped or molded from sheet or strip material and providing the necessary hinge joints and guards or hooks, and a pair of clamping members which may be made of steel wire and similarly constructed, so as to facilitate manufacture and reduce the cost thereof and arrange for easy assemblage.

With the foregoing and other objects in view, the invention will be more fully de-

scribed hereinafter, and will be more particularly pointed out in the claims appended hereto.

In the drawings, wherein like symbols refer to like or corresponding parts throughout the several views,

Figure 1 is a perspective view of a hair curler constructed according to the present invention and showing the clamping members in partly open position.

Figure 2 is a side edge elevation of the same showing the unequal spacing of the hooks or guards from the body plate, and

Figure 3 is a detail perspective view of one of the clamping members employed.

Referring more particularly to the drawing, 10 designates a body plate or strip which may be made of any suitable material, such as bakelite or other non-brittle and non-inflammable substance capable of being bent and shaped to the desired form and of inherently holding such shape after construction. The body strip 10 is of suitable length for practical purposes and is rolled over upon itself in opposite directions to provide hinge eyes 11 and 12 arranged at opposite ends of the body strip 10 and also at the opposite sides thereof. The extremities of the strip are extended from the hinge eyes 11 and 12 outwardly at a slight angle to the adjacent surface of the body strip to provide hooks 13 and 14 which preferably taper at their points or bills 15, so that such points or bills lie centrally between the lateral edges of the body strip 10. The hook 13 extends outwardly at a lesser angle than does the hook 14, so as to dispose the bill 15 of the hook 13 closer to the body strip than the opposite hook.

The hair curler is provided with a pair of clamping members 16 and 17 which are preferably of a resilient nature and which, as shown particularly in Figure 3, may be constructed of steel wire or the like. Each clamping member comprises a length of steel wire which is bent upon itself at an acute angle to provide a point 18 and which has its arms or sides diverging toward the inner end of the clamping member and bent downwardly to form spacing arms 19 adapted to lie against the opposite edges of the strip 10 and to support turned pins 20 which comprise the extremities of the length of wire.

The arms 19 are of sufficient length to permit of the snapping of the pins 20 into

the opposite ends of the hinge eyes 11 and 12 and to dispose the body part of the clamping member in suitably spaced relation from the adjacent face of the body strip 5 10. The clamping members 16 and 17 are disposed at opposite sides of the body strip 10, so that the clamping member 17 may engage beneath the hook 13, while the clamping member 16 may engage at its free 10 end beneath the hook 14. The pointed bills 15 of the hooks are adapted to overlie the bights of the points 18 of the clamping members, and the bills 15 are bent inwardly at a slight angle, so as to engage in the 15 bights for holding the clamping members from lateral displacement except when sufficient pressure is exerted thereon for freeing the clamping members.

The clamping members possess sufficient 20 resiliency to permit of the same being compressed to free the points 18 from the bills 15 of the hooks and at the same time to permit sufficient lateral deflection to escape the bills 15 as the clamping members are 25 swung outwardly into open position.

In the use of the device the body strip 10 is first placed beneath a cluster of hairs near their free ends and the clamping member 17 is then swung into position across 30 the strip or plate 10 and is forced beneath the relatively closed hook 13 so as to bind the hair curler upon the ends of the hairs. The body strip 10 and the clamping member 17 are both relatively flat and continuous 40 and present smooth uninterrupted surfaces throughout their lengths so that the hairs are uniformly clamped throughout the length of the curler. The clamping member 17 may be swung out into substantially 45 the plane of the body strip 10, so as to present a free and uninterrupted surface to the body strip as the latter is placed beneath the cluster of hairs, and so that the clamping member 17 may be swung over 50 into position without disturbing the position of the strip 10. This is important in properly locating the hair curler and if it is clamped obliquely across the hairs it naturally cannot be rolled properly and will not be efficient in carrying out its purpose.

When the device is thus clamped upon the ends of the hairs, the other clamping member 16 is swung outwardly into a straight line position with respect to the strip 10, so that the entire device may be 55 rolled in the cluster of hairs, tightly binding the latter about the hair curler until the device is brought adjacent to the scalp and into such position that the clamping member 16 may be swung freely over the rolled hairs and brought beneath the hook 14. The hook 14 is spaced away from its adjacent side of the body strip 10 sufficiently 60 to accommodate the thickened roll of hairs and so as to evenly bind the smooth 65

and continuously flat clamping member 16 over the curl formed.

It is obvious that various changes and modifications may be made in the details of construction and design of the above 70 specifically described embodiment of this invention without departing from the spirit thereof, such changes and modifications being restricted only by the scope of the following claims.

What is claimed is:—

1. A hair curler comprising a body strip rolled over in opposite directions at opposite ends and against its opposite faces to provide hinge eyes, the extremities of the strip being bent outwardly from the hinge eyes to provide hooks at opposite sides and at opposite ends of the body strip, and clamping members arranged at opposite sides of the body strip and hingedly mounted in said hinge eyes, said clamping members being adapted for engagement beneath said hooks to lie flat and in closely adjacent relation to the opposite sides of the body strip.

2. A hair curler comprising a body strip having its opposite ends rolled over upon its opposite sides to provide oppositely offset hinge eyes at the opposite ends of the strip, the extremities of said strip being bent outwardly at an angle to the body strip and provided with tapering points bent inwardly and extending toward the adjacent opposite faces of the body strip to form hooks, one of said hooks having its bill spaced a greater distance from the body strip than the opposite hook, a pair of resilient clamping members mounted in said hinge eyes and extending along the opposite sides of said body strip, each of said clamping members having a tapered point adapted to engage beneath and resiliently interlock with the bill of the adjacent hook.

3. A hair curler comprising a body strip bent at its ends and overturned upon the opposite sides of the strip to provide oppositely offset hinge eyes and hooks, a pair of spring wire clamping members disposed at opposite sides of the body strip and each comprising a length of wire bent at an acute angle intermediate its ends to form a point with a bight therein, and having its inner ends bent laterally in one direction to provide spacing arms and with its extremities turned inwardly toward each other from said arms for engagement in the opposite ends of one of the hinge eyes to pivotally support the clamping member on the body strip, said point of the clamping member being adapted for binding engagement beneath the adjacent hook and with the bill of the hook interlocking in said bight.
